LOCOMOTIVE HEADLIGHT BLIND.
APPLICATION FILED JULY 12, 1905.

2 SHEETS—SHEET 2.

UNITED STATES PATENT OFFICE.

FREDERICK J. FEWINGS, OF DULUTH, MINNESOTA.

LOCOMOTIVE-HEADLIGHT BLIND.

No. 879,377.

Specification of Letters Patent.

Patented Feb. 18, 1908.

Application filed July 12, 1905. Serial No. 269,415.

To all whom it may concern:

Be it known that I, FREDERICK J. FEWINGS, a citizen of the United States, residing at Duluth, in the county of St. Louis and State of Minnesota, have invented new and useful Improvements in Locomotive-Headlight Blinds, of which the following is a specification.

This invention relates to locomotive headlight blinds, and the object thereof is to provide a headlight blind constructed in a manner as hereinafter more specifically referred to, and which can be used in connection with any construction of locomotive headlight, either round or square, which will effectually screen or hide the light of a locomotive, said blind being particularly useful for the purpose of screening or hiding the light when a locomotive is standing upon a siding, inasmuch as the train approaching from the opposite direction will not see the headlight of the locomotive upon the siding, and all danger of confusion is thereby avoided.

The invention further resides in forming a part of the blind as a means for indicating the number of the train when the blind is moved to position to screen the headlight.

The invention further aims to provide means hereinafter more specifically referred to, whereby the blind can be operated to screen the light through the medium of the engineer from the cab or locomotive, thereby avoiding the dangerous operation of working the blind from the forward end of the locomotive.

The invention further aims to provide a locomotive headlight blind which shall be simple in its construction and arrangement, strong, durable, efficient in its use, readily operated to screening position, as well as removable from screening position, acting as a means for indicating the number of a train easily set up and comparatively inexpensive to manufacture.

With the foregoing and other objects in view, the invention consists of the novel construction, combination and arrangement of parts hereinafter more specifically described, illustrated in the accompanying drawings which form a part of this specification and particularly pointed out in the claims hereunto appended.

In describing the invention in detail, reference is had to the accompanying drawings, in which:

Figure 1 is a perspective view showing the practical application of the invention; Fig. 2 is a front elevation showing the blind projected to screen the light; Fig. 3 is a perspective view of the blind-holder with the train-number-indicating plate removed, the holder being broken away at one end; Fig. 4 is a longitudinal sectional view showing the interior of the casing and the cylinder pipe; also the manner in which the piston-rod is fastened to the blind holder; Fig. 5 is a vertical sectional view of the device; Fig. 6 is a front view showing the arrangement of the cylinder pipe and air supply pipe with respect to the casing containing the blind and blind-holder; Fig. 7 shows a modification for retracting the blind, and Fig. 8 is a view similar to Fig. 7 of another modified form.

Referring to the drawings by reference characters, wherein like reference characters denote corresponding parts throughout the several views, 1 denotes an ordinary locomotive headlight, the casing of which may be rounded, square or any shape desired; and connected with the casing of the headlight at one side is a casing 2 extending upwardly at an inclination and preferably rectangular in contour, although the shape of the casing may be of any suitable contour. The casing 2 at its upper end is flanged as at 3, and through the said flanges suitable holdfast devices extend for the purpose of securing the casing 2 to the casing 1 of the headlight. The casing 2 is furthermore supported upon a standard 4 which is fixed to the body of the locomotive. The casing 2 is adapted to contain the blind-holder, the blind and other elements associating with the blind-holder and the blind. Said blind, holder and the other elements will be hereinafter more specifically referred to. The casing 1 is provided with an opening which is arranged in suitable relation with respect to the casing 2 so that the blind-holder and blind can be projected from the casing 2, through the said opening in the casing 1 and across the front of the headlight so as to screen the light.

The blind or screen is indicated by the reference character 5, and is constructed of any material suitable for intercepting the rays of light, and the said blind 5 is folded or plaited, and has its upper side edges securely fastened in any suitable manner to the flexible bands or straps 6, 7, Figs. 5 and 7. The flexible band or strap 6 has its ends secured 110

to one of the flanges 3, and the flexible band or strap 7 has its ends secured to the other of the flanges 3, and each of the said bands or straps 6, 7 passes over the rollers 8, 9, the 5 former being arranged in the upper end of the blind-holder 10, and the latter near the lower end of the casing 1. The flexible straps 6, 7 are arranged with respect to the blind-holder 10 so that a portion of the strap 6 will lie 10 above and below the top wall of the blind-holder, and a portion of the strap 7 will lie above and below the bottom wall of the blind-holder, or in other words, the straps 6, 7 are adapted to inclose the top and bottom 15 walls of the blind-holder; and to obtain such an arrangement, the said top and bottom walls of the blind-holder are connected to the front and rear walls at a point removed from the longitudinal edges thereof. That portion 20 of the strap 6 which is arranged below the top wall of the blind-holder is secured to one side of the blind, and that portion of the strap 7 which is arranged above the bottom wall of the blind-holder is secured to the 25 other side of the blind. By such an arrangement, when the blind is projected forwardly, it will automatically open, as will be evident.

The blind-holder 10 which also forms a part of the blind when the latter is projected 30 so as to intercept the rays of light, as best shown in Fig. 3, is formed of a pair of vertically-extending plates 11, 12, the former being the front wall of the blind-holder and the latter the rear wall. These plates are connected together near their top through the 35 medium of the plate 13 which forms the top wall of the blind-holder. This plate 13 is not as long as the plates 11, 12, and the said plates 11, 12 at their bottom are connected 40 together by a plate 14 which forms the bottom wall of the blind-holder. The plate 14 is not as long as the plates 11, 12. The plates 11, 12 at their upper or forward ends are furthermore connected together through the 45 medium of a pair of shafts 15 which carry the rollers 8. The plates 11 and 12 are provided with an opening 16, and the opening in the plate 11 has the longitudinal edges thereof provided with outwardly-extending angular 50 projections 17 which form a seat as well as a retaining means for a train-number-indicating plate or plates 18. The plate or plates 18 have the desired numbers cut therein so that when in position and the 55 blind projected, the light will show through the numbers so that any one can readily ascertain the number of the train at the same time that the headlight is screened. Owing to the arrangement of the holder 10 and plate 60 18 with respect to the blind 5, the said holder 10 and plate 11 form a part of the blind 5 when the blind is projected.

In Figs. 1, 2, 4 and 5 of the drawings, the blind is projected through the medium of 65 fluid pressure, preferably in the form of air,

said pressure acting against a means to be presently described so as to impart movement to said means, and thereby project the blind. The blind is retracted also through the medium of fluid pressure, preferably air. 70 For the purpose of obtaining the projecting and retracting of the blind, as well as the holder, through the medium of fluid pressure, preferably air, two air supply pipes are provided, and which are indicated by the 75 reference characters 19 and 20. These pipes 19 and 20 lead into the locomotive cab, and are provided with suitable regulating valves under the control of the engineer so that whenever it is desired to project or retract 80 the holder and the blind, the regulating valves are suitably operated so that a pressure of air can be supplied to operate the means to project and retract the blind and holder which will now be described. The 85 pipe 19 leads into a cylinder 21 arranged in front of the casing 2, but if desired, the cylinder 21 can be arranged at the rear of the casing 2. Within said cylinder 21 operates a piston 22 connected to a piston rod 23 90 which projects through the upper or forward end of the cylinder 21 and is secured to a depending lug 24 carried by the holder 10. Therefore, it will be evident that if pressure is supplied to the cylinder 21 and against the 95 piston 22, the same will be moved forward carrying the holder 10 and blind 5 there-with, thereby projecting the blind. To retract the blind and holder, the cylinder 21 at its forward end is provided with an opening 100 which communicates with a branch pipe 25 leading into the pipe 20. So, therefore, if pressure is supplied through the pipe 20 into the branch 25 and from there into the forward end of the cylinder 21, the pressure will 105 act upon the piston 22 and move the same in what may be termed a rearward direction, and consequently the holder 10 and blind 5 will be returned to within the casing 1. The branch 25 is connected with the cylinder 21 110 through the medium of the cap 26 which opens into said cylinder 21, or rather, which communicates with one end of the cylinder 21, the latter being open so that communication will be had between the cap 26 and the 115 cylinder 21.

A means is provided so that the blind 5 can be readily used for different-sized headlights, and in this connection all that is necessary, is to limit the projecting movement of the 120 blind. Such limiting movement can be had by providing the piston-rod 23 with a plurality of removable stops 27.

In Fig. 7 of the drawings, a modified means is shown for retracting the holder and blind, 125 and in this connection, the pipe 20, branch 25 and cap 26 are dispensed with, and in lieu thereof, a strong spiral spring 28 is employed which has one end fixed to the casing 1, as at 29, and its other end fixed to the holder 10, 130

as at 30. It will be evident that when pressure is removed from the piston 22 that the action of the spring 28 will retract the holder and blind within the casing 1.

5 In Fig. 8 of the drawings another modified means is shown for retracting the holder and blind, and which consists of constructing the straps 31 of elastic material, the action of which when pressure is relieved upon the 10 piston 23, will cause the retraction of the holder and blind.

In Fig. 8 a modified means is shown for increasing or diminishing the diameter of the blind to suit various sized headlights, and 15 which consists in forming in what may be termed the inner end of the blind, a plurality of openings for the reception of a bolt 32 which secures the blind to the operating straps 31. Thus it will be seen that if the 20 blind is secured to the straps 31 by the bolt 32 being placed in the outer opening, it will not be possible to extend the blind to as great a diameter, as when the bolt is placed in the lower opening. This explanation also 25 applies to the removable stops 27, shown in Fig. 4.

From the foregoing, it is evident that an exceedingly simple and efficient construction of blind for locomotive headlights which can 30 be used in connection with any and all constructions of headlights, can be operated entirely from the locomotive cab, and when in use, will not only completely screen or blind the headlight, but will also permit of the 35 number of a train being clearly indicated.

Although it has been stated that the invention is particularly adapted for the purpose of screening locomotive headlights when the said locomotive is upon a siding, 40 it will, of course, be understood that the invention is capable of other uses as some signal systems utilize a locomotive headlight for the purpose of transmitting signals, and it is obvious that owing to the ease and facility of operation and the speed with which the blind or screen can be opened or closed, that the invention would be particularly adapted to this system.

Other uses and advantages will also be apparent to those skilled in the art to which it 50 belongs.

Having thus fully described my invention, what I claim as new and desire to secure by Letters Patent, is:

55 1. A casing containing a foldable blind, a fluid-pressure operated means for expanding and projecting the blind, and a fluid-pressure operated means for retracting the blind.

2. An expandible and retractable locomotive headlight blind having means for increasing or diminishing the diameter thereof when expanded.

3. An expandible and retractable locomotive headlight blind having means for increasing or diminishing the diameter thereof

when expanded, combined with means forming a part of said blind for indicating the number of a train.

4. An expandible and retractable locomotive headlight blind having means for increasing or diminishing the diameter thereof when expanded, combined with a fluid-pressure operated means for expanding and retracting the blind. 70

5. An expandible and retractable locomotive headlight blind having means for increasing or diminishing the diameter thereof when expanded, combined with means forming a part of said blind for indicating the number of a train, and fluid-pressure operated means for expanding and retracting the blind. 75

6. A headlight casing, a casing arranged exterior of said headlight-casing and containing a foldable blind, a fluid-pressure-operated piston arranged exterior of the said blind-casing and connected with the blind for projecting it into said headlight casing when the piston is operated, and means for supplying fluid pressure against said piston 90 for operating it in a counter direction to retract the blind. 85

7. A device for screening a locomotive headlight, comprising an expandible and retractable blind, a holder therefor provided with openings, a train-number-indicating means carried by the holder and arranged in suitable relation with respect to said openings, a fluid-pressure-operated means for projecting and expanding said blind and for 100 projecting said holder and means across the path of light, and a fluid-pressure-operated means for retracting said blind, holder and means. 95

8. A locomotive headlight blind, comprising an interchangeable means for indicating the number of a train, combined with a fluid-pressure-operated means for expanding the blind and projecting said train-number-indicating means, and a fluid-pressure-operated 105 means for retracting said blind and train-number-indicating means. 110

9. An apparatus of the character described comprising a casing, a holder arranged therein and provided with an interchangeable 115 train-number-indicating means, a blind arranged, in said holder, fluid-pressure-operated means for projecting the blind and holder in advance of a locomotive headlight, thereby screening the same, a fluid-pressure-operated means for retracting the blind and holder. 120

10. A foldable blind adapted to be projected into a headlight casing, a holder moving with and carrying said blind, a fluid-pressure-operated means for projecting said holder and blind, means for connecting the blind to the holder, whereby as the said holder is moved in one direction, the blind will be expanded and when the holder is 125 130

- moved in the opposite direction, the blind will be closed and drawn within the holder and a fluid-pressure-operated means for retracting the holder.
- 5 11. A device for screening locomotive headlights comprising an expandible and retractable blind, a projectable and retractable holder therefor, having the blind connected thereto and provided in its front 10 and rear face with openings, and further provided on its front face with angular projections arranged in close proximity to the opening in said front face, a train-number-indicating means seated in and retained by 15 said projections against said holder, a fluid-pressure-operated means for projecting said holder, blind and means across the path of light, causing thereby the expanding of the blind, and a fluid-pressure-operated means 20 for retracting the holder, blind and train-number-indicating means.
12. A device for screening locomotive

headlights, comprising an expandible and retractable blind, a projectable and retractable holder therefor having the blind 25 connected thereto and provided with openings and further provided on one face with angular projections arranged in close proximity to the openings in said face, a train-number-indicating means seated and retained in position by said angular projections, a fluid-pressure operated means for projecting said blind, holder and means across the path of light, thereby screening the same and for retracting said blind, holder and 30 means to inoperative position.

In testimony whereof I have hereunto set my hand in presence of two subscribing witnesses.
